(57) **CLAIM**

The ornamental design for an add-on unit for a media preparation apparatus, as shown and described.

DESCRIPTION

FIG. 1 is a front, right, top, perspective view of an add-on unit for a media preparation apparatus showing the new design.

FIG. 2 is a rear, left, top perspective view of the add-on unit for a media preparation apparatus of FIG. 1.

FIG. 3 is a right side elevation view of the add-on unit for a media preparation apparatus of FIG. 1.

FIG. 4 is a left side elevation view of the add-on unit for a media preparation apparatus of FIG. 1.

FIG. 5 is a top plan view of the add-on unit for a media preparation apparatus of FIG. 1.

FIG. 6 is a bottom plan view of the add-on unit for a media preparation apparatus of FIG. 1.

FIG. 7 is a front elevation view of the add-on unit for a media preparation apparatus of FIG. 1.

FIG. 8 is a rear elevation view of the add-on unit for a media preparation apparatus of FIG. 1.

FIG. 9 is a front, right, top, perspective view of an add-on unit for a media preparation apparatus showing the new design.

FIG. 10 is a rear, left, top perspective view of the add-on unit for a media preparation apparatus of FIG. 9.

FIG. 11 is a top plan view of the add-on unit for a media preparation apparatus of FIG. 9.

FIG. 12 is a bottom plan view of the add-on unit for a media preparation apparatus of FIG. 9.

FIG. 13 is a front elevation view of the add-on unit for a media preparation apparatus of FIG. 9.

FIG. 14 is a rear elevation view of the add-on unit for a media preparation apparatus of FIG. 9.

FIG. 15 is a right side elevation view of the add-on unit for a media preparation apparatus of FIG. 9; and,

FIG. 16 is a left side elevation view of the add-on unit for a media preparation apparatus of FIG. 9.
